THE-WIRE TIGHTENING AND TWISTING DEVICE

Leland M. Van Slyke, North Hollywood, Calif.

Application March 14, 1932, Serial No. 598,628

15 Claims. (Cl. 140—123.5)

My present invention relates to a tie wire tightening and twisting device and consists particularly of improvements over my former patent for tie wire tightening and twisting device issued 5 March 10, 1931, Patent No. 1,795,625.

The objects of this invention are:

First, to provide a means whereby the tie wire of forms or structures may be drawn tightly and at the same time be twisted, bent, or formed to 10 fit jaws for gripping and twisting the tie wire;

Second, to provide means of this class in combination with or forming a part of the twisting device;

Third, to provide a pair of adjustable jaws for 15 gripping the end portions of tie wires of various gages or sizes so that the same tool may be used with only slight adjustment;

Fourth, to provide novelly constructed jaws for accommodating the device to various sizes of 20 wires without otherwise adjusting the device or changing its function or manipulation;

Fifth, to provide a device of this class in which one jaw is adapted to enter another jaw and adapted to enter the latter jaw in only one position, 25 said position between the two jaws depending upon the size of wire used;

Sixth, to provide a device of this class in which the tie wires used can be clamped only on one side or in one position of the jaws;

Seventh, to provide novelly constructed means 30 for forcing the two jaws together and a novel relation of said means to the other portions of the structure; and

Eighth, to provide as a whole a novelly constructed device of this class and one which is 35 simple and economical of construction proportional to its functions, durable, efficient, easy to operate and which will not readily deteriorate or get out of order.

With these and other objects in view as will appear hereinafter, my invention consists of certain novel features of construction, combination and arrangement of parts and portions as will be hereinafter described in detail and particularly 45 set forth in the appended claims, reference being had to the accompanying drawing and to the characters of reference thereon which form a part of this application, in which:

Figure 1 is a sectional view of a form structure 50 and a tie wire in connection therewith showing my device fragmentarily in position for tightening the tie wire and forming the end thereof; Fig. 2 is a fragmentary longitudinal sectional view thereof taken through 2—2 of Fig. 3 showing by 55 dotted lines the clamping position of one of the

jaws and showing fragmentarily by dotted lines a tie wire in clamped position; Fig. 3 is a partial sectional and partial elevational view thereof with the sectional portion taken through 3—3 of Fig. 2, showing fragmentarily by dotted lines, the 60 clamping lever in the clamping position; Fig. 4 is a fragmentary side view of the jaw portion of the tool; and Fig. 5 is a sectional view thereof taken through 5—5 of Fig. 2.

Like characters of reference refer to similar 65 parts and portions throughout the several views of the drawing.

The tool is supported in a long tubular handle 1 about which the tool is gripped with one hand. At one end of the handle is secured the pivot 70 member 2. This pivot member consists primarily of a pointed portion 2a at its extended end, a claw 2b intermediate its ends and at its outer side, and a forming portion 2c at one side and forming a portion of the claw portion. The extended portion of the pivot member is offset and positioned parallel to the axis of the handle. The pointed portion 2a is adapted to be positioned against and to enter a portion of the form structure F, shown best in Fig. 1, and is prevented from entering such form structure an excessive distance by the disc 2d positioned inwardly from the outer end of the pointed portion. The claw 2b is similar to that in common use and is preferably made by a notch in the outer flange of the T-shaped 75 pivot member. The forming portion 2c is preferably disc like with a backwardly extended edge portion 2e. These portions are formed at the outer side of the pivot member, at the side of the claw towards the pivot portion. The portion 2e of the forming portion is preferably a portion of the outer flange of the T-shape and is preferably sharp, as shown in Fig. 1, to facilitate the gripping of the tie wire. As the end of the tie wire is inserted into the claw for tightening the same in the form structure, the same is bent around the disc 2c and thereby bent substantially into such shape as to facilitate the positioning of this bent portion around one of the jaws, as will be described hereafter.

In the handle 1 is rotatably mounted a tube 3 which extends beyond the opposite ends of the handle 1 and is provided at one end with a jaw or jaw member 4 and at its opposite end with an enlarged portion 5. The jaw 4 is preferably 100 screwably secured to the tube 3. In and coaxially with the tube 3 is longitudinally shiftably mounted a rod 6 which is preferably round as shown. At one end of this rod is screwably mounted the 105 jaw or jaw member 7 which forms with the jaw 110

or jaw member 4 the clamping means for the tie wire. At the opposite end of the rod 6 is pivotally mounted the handle 8 by means of a pin 9 as will be described hereafter.

5 The longitudinally outer side, or the portion of the jaw or jaw member 4, which is extended towards the jaw member 7, is provided with a pair of jaws, as indicated by 4a in Fig. 2, which form with the plane passing through the axis of 10 the rod 6 substantially dihedral angles, so that both jaws of the member 4 engage or clamp the wire. The jaw member 7 is preferably round with its axis at right angles to the axis of the rod and is mounted on the threaded portion 6a 15 of the rod. The jaw member 7 is secured to the threaded portion of the rod by a set screw 10. The pitch of the threads on the threaded portion 6a is substantially such that the pitch is equal to the difference in diameter of the wire of adjacent gages so that when the jaw member 7 is 20 rotated a complete revolution the tool will accommodate and clamp the wire of the next larger or smaller size.

It will be here noted that if the ends of the tie 25 wire become overlapped or lie one over the other, the jaw members 4 and 7 will be required to be positioned at least twice the thickness of the diameter of the wire used. Such overlapping or crossing of the tie wire will be at the inner side 30 of the jaw member 7. In order to accommodate such overlapping or crossing there is provided a clearance 4b at the inner portions of the jaws 4a. Such clearance will permit such crossing of the wires and still clamp the same between the 35 two jaw members.

It will also be noted that if the jaws do not tightly grip the wire when the handle 8 is shifted from the solid to the dotted line position as will be described hereafter, the jaw member 7 is 40 adjusted with respect to the jaw member 4 one-half the distance of the pitch of the thread on the rod 6. In order to accomplish the latter adjustment, the jaw member 7 is removed and the rod 6 is withdrawn and rotated one-half revolution 45 with respect to the tube 3. The jaw member 7 is then again screwed into position and tightened.

The jaws 4a are positioned at the opposite sides of a recess, forming a recessed jaw, the opposite ends of which are enclosed by walls 4c and 4d. 50 The portion of the jaw member 7 through which the set screw 10 extends, and the corresponding recess portion of the jaw member 4 are preferably longer than the diametrically opposite portions of the jaw members 7 and 4 respectively so that the jaw member 7 can enter the recessed jaw in only one position.

The wall 4d, which is positioned further from the axis of the rod 6 than the wall 4c is partially cut away, as shown in Fig. 4, so that the tie 60 wires may be inserted only between the long portions or jaws of the jaw members.

The enlarged portion 5 is provided with longitudinal grooves 5a into which the ends of the pin 9 extend and which permit longitudinal shifting of the pin with the rod 6. These longitudinal 65 grooves hold the two jaw members nonrotatably with respect to each other but permit longitudinal shifting of the one with respect to the other.

The handle 8 is provided with a bifurcated 70 portion 8a which straddles a reduced portion 6b of the rod 6 and is pivotally connected thereto by the pin 9. The peripheries of the furcations of the bifurcated portion 8a are preferably spirally shaped, as shown, so as to form a cam for gradually forcing the jaws relative to each other

and clamping the tie wire therebetween, the unclamped and clamping positions being shown respectively by solid and dotted lines in Fig. 3. Between the bifurcated portion 8a and the inner end of the enlarged portion 5, that is, the inner end of the slotted portion of the member 5 into which the bifurcated portion extends, is preferably positioned a pair of axially spaced apart rollers 11 against which the peripheral curved portions of the bifurcated portion bear, to facilitate the drawing or forcing the jaws toward and from each other. The axes of these rollers preferably intersect at right angles the axis of the rods. These rollers are held in position by a set screw 12. If desired, several pairs of rollers may be used.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a tie-wire tightening and twisting device, a wire tightening device, one end of the device having means upon which said device may be pivoted and having means at the side thereof for gripping the tie-wire and other means at the side thereof to facilitate the bending of the end portion of the tie-wire.

2. In a tie-wire tightening and twisting device, a wire tightening device, one end of the device having means upon which said device may be pivoted and having means at the side thereof for gripping the tie-wire and having a jaw inwardly from the aforementioned means and forming a part thereof for facilitating the bending of the end portion of the tie-wire.

3. In a tie-wire tightening and twisting device, a wire tightening device, one end of the device having means upon which said device may be pivoted and having at the side thereof a claw for clamping the end portion of the tie-wire, one side of the claw over which the end portion of said tie-wire extends being shaped to facilitate the bending of the end portion of the tie-wire.

4. In a tie-wire tightening and twisting device a pair of jaws for gripping the end portions of the tie wire, and a pivot member offset with respect to said jaws and adapted to pivotally support said jaws, said pivot member having means in connection therewith to facilitate the bending of the end portions of said tie wire in conformity to one of said jaws.

5. In a tie-wire tightening and twisting device a pair of jaws for gripping the end portions of the tie wire, and a pivot member offset with respect to said jaws and adapted to pivotally support said jaws, said pivot member having a claw for gripping the end portions of said tie wire, the side of said claw extending toward the end of the pivot member, being shaped to facilitate the bending of the end portions of said tie wire in conformity to one of said jaws.

6. In a tie-wire tightening and twisting device of the class described, a pair of jaws, and lever means for forcing said jaws together and for rotating both of said jaws, one of said jaws having a cylindrical shaped convex surface and being adjustable relative to the other independently of said lever means and the other jaw having a circular concave portion.

7. In a tie-wire tightening and twisting device of the class described, a handle, a pair of jaws rotatably mounted at one end of the handle, and means for forcing said jaws together, one of said 5 jaws having a cylindrical shaped convex surface and being adjustable relative to the other jaw independently of said means and the other jaw having a circular concave portion. 80
8. In a tie-wire tightening and twisting device of the class described, a handle, a pair of jaws 10 rotatably mounted at one end of the handle, and lever means for forcing said jaws together and for rotating both of said jaws, one of said jaws having a cylindrical shaped convex surface and being 15 adjustable relative to the other independently of said lever means and the other jaw having a circular concave portion. 85
9. In a tie-wire tightening and twisting device of the class described, a long handle, a tube rotatably mounted within said handle, a jaw secured to one end of said tube beyond one end of 20 said handle and having a circular shaped concave surface, a rod longitudinally shiftably mounted within said tube, a second jaw longitudinally adjustably mounted at one end of said rod 25 in spaced relation to the first jaw and having a cylindrical shaped convex surface, and means at the opposite end of said handle for shifting said jaws with respect to each other. 95
10. In a tie-wire tightening and twisting device 30 of the class described, a handle, a jaw mounted on said handle and provided at its outer side with a circular surfaced recess-like jaw, a second jaw with a circular convex surface shiftably mounted with respect to the first jaw and adapted to 35 enter the latter. 100
11. In a tie-wire tightening and twisting device 40 of the class described, a handle, a circular surfaced recess-like jaw mounted upon said handle, a rod longitudinally shiftably mounted through said jaw, a second jaw with a circular convex surface adjustably mounted upon said rod and adapted to enter said recess-like jaw, and means 45 for adjusting said jaws relative to each other. 105
12. In a tie-wire tightening and twisting de- 50 vice of the class described, a handle, a recess-like jaw mounted upon said handle, a rod longitudinally shiftably mounted through said jaw, a second jaw adjustably mounted upon said rod and adapted to enter said recess-like jaw, and means 55 for adjusting said jaws relative to each other, one end of the second jaw extending a greater distance from the axis of said rod than the other end of said second jaw and adapted to enter the recess-like jaw in one position only. 80
13. In a tie-wire tightening and twisting device of the class described, a jaw member, a rod longitudinally shiftably mounted with respect to said 60 jaw member, a second jaw member mounted on said rod, the first jaw member having a recessed jaw portion adapted to receive the second jaw member, one end of the first and second jaw members being positioned a greater distance from the axis of said rod than the other ends of 65 said jaw members, the first jaw member being provided with a wall at its short end and adapted to receive tie wires through its long end, and means for adjusting said jaw members towards and from each other. 90
14. In a tie-wire tightening and twisting de- 70 vice, a wire tightening member, one end of said member having means upon which said member may be pivoted and having a tapering slot at the side thereof for gripping a tie-wire and having a circularly shaped wire forming jaw adjacent said 75 slot adapted to receive the tie-wire near the ends and form them in curved form while tightening said tie-wires. 100
15. In a tie-wire tightening and twisting de- 80 vice, a wire tightening member, one end of the 85 member having a pointed portion upon which said member may be pivoted and having a converging slot at the side thereof for gripping the tie-wire, and an enlarged rounded tie-wire forming portion adjacent thereto between said slot 90 and said point adapted to facilitate the bending of the end portion of the tie-wire simultaneously 95 with the tightening of said wire. 110
